J. C. JOHNSON

ROTARY OIL BURNER

Filed Dec. 7, 1922

FIG. 1

FIG. 3

FIG. 2

FIG. 4

Jesse C. Johnson
INVENTOR.

BY Gustav D. Wiegand
ATTORNEY

UNITED STATES PATENT OFFICE.

JESSE C. JOHNSON, OF OAKLAND, CALIFORNIA.

ROTARY OIL BURNER.

Application filed December 7, 1922. Serial No. 605,470.

To all whom it may concern:

Be it known that I, JESSE CLAUDE JOHNSON, a citizen of the United States, residing at 940 Arlington Ave., Oakland, in the county of Alameda and State of California, have invented certain new and useful Improvements in Rotary Oil Burners, of which the following is a specification.

The present invention relates to an improvement in rotary oil burners employing a centrifugal atomizer or atomizing cup for reducing the oil into a fine spray, and is more particularly an improvement in the general class described and set forth in my co-pending application filed March 28, 1922, Serial No. 545,989.

A further object of my invention is to provide an improved means or construction by which the oil is fed to the interior of the cup, and obtain a quicker and more effective method of oil supply to the revolving cup than has hitherto been obtained, my purpose being to feed the oil in relatively small streams irrespective of the amount of oil admitted into the cup. When thus applied, the progression of the oil through the cup toward the outer atomizing edge thereof will be as a series of relatively thin stream lines of oil which will break off the outer atomizing edge of the cup into a very fine spray.

My invention can best be seen and understood by reference to the accompanying drawings, where the improvement embodying my invention is applied to an atomizing cup of well known character and in which—

Figure 1, is a longitudinal vertical section through the burner;

Fig. 2, is a cross-section on line A—A, Fig. 1.

Fig. 3, is a perspective view of the spider member within the atomizing cup; and

Fig. 4, is a side elevation of the spider member.

Referring to the drawings, where like designating characters indicate the same parts throughout the several views:

A rotary atomizing cup 1 is removably mounted upon the free end of an axle 2, connecting with any suitable mechanism (not shown) for rotating it and the cup.

The atomizing cup consists of a cylindrically shaped casing, the outer open end 3 extending into the fire-box. The opposite

end 4 of the casing is partially closed by 65 means of an inwardly directed flange 5.

Suitably secured within the atomizing cup 1 is a spider member 6, of cup-shaped contour. A series of longitudinally disposed helical slots 7, in spaced relation to each other, are formed through the contiguous portion 8 of its body, and forming grooves through its base 9. The body portion of the said spider member forming in conjunction with the aforesaid inwardly directed flange 65 5, an oil receiving chamber 10, at the inner end of the atomizing cup.

This spider member is in this instance provided for two purposes; first, that of supporting the atomizing cup, by means of 70 a securing bolt 11, to the free end of the axle 2, and secondly, that of forming a series of helically disposed oil-orifices within the atomizing cup 1, whereby, when the cup is 75 revolved, the oil, initially fed into the oil receiving chamber 10 of the atomizing cup, will be directed out of said chamber and deposited onto the interior surface 12 of the cup, in a plurality of relatively thin lines or streams extending laterally toward the 80 open end.

This is of considerable importance, as the atomizing cup, when revolving at a high speed, causes the oil to be discharged by 85 centrifugal force, through the helically disposed slots of the spider member and projected forward onto the interior surface of the atomizing cup. In actual operation, it is found that the fuel oil delivered to the receiving chamber 10 is more freely discharged therefrom and in greater quantities, by means of said helical slot construction 90 of the spider member, than if the slots of the said spider member were arranged longitudinally and in axial alinement with the 95 cup.

The angle of entrance and discharge of the fuel oil by means of said spider member is in such proportions as to provide for an increased bulk of fluid. The size of the 100 helically bored spider member, including the cup, may, of course, be varied in accordance with variations in size of the burners in which they are to be used. The direction of motion is shown by an arrow. The supply of fuel oil is regulated by a controlling valve, (not shown) so that the feed of oil 105 may be increased or diminished.

While the burner here described is more or less specific in construction and design, I wish it understood that it may be varied within the limits of the scope of the claims; 5 similarly, that the materials and finish of the several parts may be such as the experience and judgment of the manufacturer may dictate.

What is claimed as new is:—

- 10 1. In combination with a rotary atomizing cup, a spider member, of cup-shaped contour, having a base and a contiguous body portion, said body portion being provided with a plurality of helically disposed slots 15 and terminating in grooves through the said base.
2. In combination with a rotary atomizing cup, a cupped spider member, having a base and a contiguous body portion provided with

a plurality of helically disposed slots, in spaced relation to each other, and ending into grooves through the said base.

3. In combination with a rotary atomizing cup, a cup-shaped spider member, having a base and a contiguous body portion, said body portion being provided with a plurality of helically disposed slots, in spaced relation to each other, and terminating in grooves through the said base, the helix of said slots being in a direction opposite to the rotation of the atomizing cup.

In testimony whereof I have affixed my signature in the presence of two witnesses.

JESSE C. JOHNSON.
